UNITED STATES PATENT OFFICE

LLOYD E. GOODYEAR, OF CHICAGO, ILLINOIS

LOOSE LEAF BINDER

Application filed November 29, 1929. Serial No. 410,302.

This invention relates to loose leaf binders. Heretofore the means employed to bind loose leaf or note paper has been by means of rings or posts, which latter, obviously, tended to mar the surface of the desk or table on which the binder might temporarily be resting, and which, in other respects, is cumbersome and undesirable.

The primary object of my invention is to provide an economical and efficient loose leaf binder that can be made in sufficient quantities at a price to make it available particularly for students' use. Heretofore, it has been a difficult matter to procure for students' use satisfactory loose leaf binders for demonstrating ledger and journal practice at a price that makes the same possible for individual student's use, since the ordinary commercial loose leaf binders are made of heavy, expensive and durable materials in contemplation that the same will have long daily use in the accounting room or office in the ordinary commercial practice where the initial cost of the binder is not as much of a desideratum as when the same is intended for the use of students.

A further object of my invention is to provide a loose leaf binder which will hold the loose leaves securely in place and permit the pages composing said binder to be utilized and written upon to within a very short space removed from the binding edge, and will not mar the desk or table with which said loose leaf binder may come into contact.

In the accompanying drawings, like characters are applied to like portions of the structure shown.

Fig. 1 represents a top plan view of the binder showing the same in open position.

Fig. 2 is a cross sectional view of the binder taken on line 2-2 of Fig. 1.

Fig. 3 is a cross sectional view showing the same parts as in Fig. 2, the binder being in closed position.

Fig. 4 is a fragmentary, longitudinal, sectional view of the binder in closed position taken on the line 4-4 of Fig. 3, looking in the direction indicated by the arrows.

Fig. 5 is an enlarged, fragmentary view

showing in greater detail parts as illustrated in Fig. 3.

Fig. 6 is a horizontal, sectional view of the upper binder bar showing the slots for the insertion of the binding screws.

55

In the preferred form of my invention as illustrated in the drawings, the reference character A designates generally cover backs which in the embodiment shown, are preferably made of some firm, tough material as fiber board or even a good grade of relatively stiff paper board. The cover backs may obviously be made of any suitable stiff protective material and one of the important features of my invention resides in the manner in which I hingedly or flexibly connect the cover backs A with the binder bars H.

In normal use my improved loose leaf binder is adapted to serve as a means for securing and protecting a plurality of loose leaves bound together thereby in book form in the manner generally illustrated in the drawings, Figs. 1 to 5 inclusive, these removable or loose leaves which may be ledger or journal leaves as used, for example, in accounting, being designated by reference character B.

The reference character C is shown applied in the drawings to designate the head of a specially formed binder screw of which two or more, preferably two, will be used to unite the binder bars and covers of each loose leaf binder in the manner as hereinafter described.

The screws will be provided with threaded shanks designated by reference characters G and G'. The heads C of these screws will be cylindrical in form and preferably be provided with a slot as illustrated to take a tool as a screw driver for operating them.

The binder bars H, of which there are two used in each binder unit, one obviously of each being hingedly connected with each of the cover backs A, are of special formation being formed of metal and rectangular or substantially square in cross-section as illustrated in Figs. 2, 3 and 5.

Since economy of construction is one of the essential features of my invention, this result is obtained partly by reason of the fact that

85

80

85

90

95

100

the binder bars H may be made of sheet-metal formed by suitable dies in an economical manner from flat or sheet material and soldered if desired at the seam. One of these binder bars will be suitably slotted as designated at F and F', Figs. 4 and 6, while there will be corresponding openings for the threaded shanks G and G' of the screws in the hollow interior of the opposite binder bar. The slots will preferably be what are generally termed keyhole slots comprising a substantially elongated slot terminating at one end in a somewhat enlarged opening, as shown most clearly in Fig. 6. The enlarged openings in these keyhole slots will be of sufficient size to permit the passage into the interior of the slotted binder bar H of the cylindrical heads C of the screws.

In the other binder bar H opposite the keyhole slots F and F' and preferably registering with the extremity of the contracted portion of the slot opposite the enlarged portion, openings will be provided through which the threaded shanks G and G' of the screws will freely pass, and metallic screw-threaded blocks E, substantially filling in cross-section the rectangular hollow space on the interior of the metallic bar H, as illustrated in Figs. 2 to 5 inclusive.

The ends of the rectangular binder bars H may be left open so that the threaded blocks or nuts E may be easily introduced and secured in position, thus resulting in a cheap construction of the binder bars H, enabling them to be made largely by stamping operations while the threaded blocks or nuts E may be made on automatic machines.

Opposite the extremities of the openings for the screw heads C and the screw shanks G and G', openings K and M will be formed through the outer walls of the binder bars H, the opening designated at K being designed to permit the introduction of a suitable tool as a screw driver to co-operate with the slotted head C of the screw, while the opening designated at M in the opposite bar H will be utilized to permit the lower end of the screw to pass close to the outer surface of the binder bar H when a very few leaves B are in position in the binder.

To afford the desired range of flexibility in making a hinging connection between the rigid cover backs A and the binder bars H, I terminate the material or board of the cover backs A a short distance from the wall of the binder bars H leaving a space or gap slightly wider than the thickness of the cover backs A to allow proper hinging of the covers to the position of Fig. 2 as designated in Fig. 3 by reference character P the same being of a length approximately equal to the thickness of the cover back.

A hinging or flexible connection between the cover backs A and the binder bars H, I obtain in the following manner:

By the use of glue or other suitable adhesive, I attach suitable flexible material D, cut of the desired size to cover the metallic binder bars H and to extend over the normal inner faces of the cover backs A for attachment purposes, thus securing flexible hinging connections between the cover backs and the binder bars in a simple and economical manner. The flexible material used for covering the binder bars and for gluing to the cover backs is preferably a good firm grade of woven canvas or other flexible textile material as designated generally by the reference character D.

The manner in which the canvas is applied will be best understood by reference to Figs. 3 and 5 from which it will be seen that I apply the canvas to the inside faces of both cover backs A beginning about as indicated at the reference character S in Fig. 3 and I cut the canvas so that it will extend and bridge the gap or space P; thence to cover the co-operating inner faces of the metallic binder bars H; thence the canvas D will be wrapped and glued around the three remaining sides of the binder bars which are preferably rectangular in cross section as shown and I prefer that the canvas also extend around the co-operating inner surfaces of the binder bars as illustrated in the drawings so that the edges of the canvas opposite the edges S will be glued in direct contact with the opposite meeting faces of the binder bars which will result obviously in two thicknesses of canvas on these opposite inner faces and will result in a secure fastening for the canvas at this edge.

The canvas D will also be preferably extended on diametrically opposite sides to afford flaps designated at T for pasting flat on the outside of the cover backs A. The canvas covering will obviously be cut away as illustrated in the portions over the binder bars to permit the openings, as designated at K and M, for the screws C, G to be accessible and also permit the keyhole slots F, F' to be accessible.

From the above description it will be seen that I have provided cover backs and binder bars hingedly connected in cooperating pairs that are economical to manufacture, in fact, they may be made so cheaply as to be available for the use of students taking commercial courses in business instruction where ledgers, journals and day books of the loose leaf type are desired to be used, under which conditions it will be seen that not only is an economical binder desirable but the number of loose leaves B that will be used in such binders, particularly for students, use will ordinarily not be very great, although there may be considerable variation which may be compensated for or taken care of by reason of the fact that the threaded screw shanks G, G', in cooperation with the threaded nuts

E, will permit of rather a wide range of adjustment, and while I show the threaded screw shanks G and G' of a substantially uniform length in all of the views, it will be apparent to those skilled in the art that other pairs of screws of different lengths may be substituted to accommodate the binder to various quantities of leaves and that I have provided an economical and useful construction of flexibly connected cover backs and binder bars that presents a binder of book form that may be conveniently opened to a very flat position as illustrated particularly in Figs. 1 and 2 where the leaves B will lie relatively flat for writing or inscribing entries thereon, and whether the binder book be in the open position as shown in Figs. 1 and 2 or in the closed position as shown in Fig. 3, all metallic parts of the binder bars 20 are canvas covered and protected so that the same may be conveniently used upon finished surfaces such as polished furniture without abrading or injuring the same.

The mode of manipulation of my loose leaf binder will be apparent from the foregoing description when it is understood that the leaves B will be perforated to receive the threaded screw shanks G and G' in the usual manner; such perforations as is common in this art may take the form of keyhole slots in which the narrow part of the slots will be of somewhat less width than the diameter of the threaded screw shanks G and G'.

In operating my binder, a screw driver or analogous tool will be inserted in the slot in the head portion C of the screws by passing the tool through opening K in the binder bar and by rotating the same it will be seen that the binder bars may be tightened upon the leaves to firmly secure them in position over the range of adjustment provided by the length of the threaded screw shanks G and G', while the relatively fixed position of the screw-threaded nuts or blocks E in one of the cooperating binder bars H together with the fact that the cylindrical head C of the screw will be contained in the opposite binder bar will prevent objectionable looseness between the parts even during periods of adjustment.

In assembling and disassembling the binder bars H, which it will be seen from the foregoing description, must be made in cooperating pairs, the binder bar H which receives the threaded nut or block E, as illustrated in the drawings, may have one of the screws inserted and screwed into the block in what is the lower bar H, in Figs. 3, 4 and 5. The upper binder bar H, as shown in Figs. 3 to 5 inclusive, and having the key hole slots as illustrated in Fig. 6 and carrying the flexibly connected or hinged cover back, will be brought into a position so that one of the enlarged openings F or F', as the case 65 may be, of the key hole slots, will register

with the cylindrical head C of the inserted screw when the head will be entered in the slot and slid to the narrow end of the slot. The operator with the parts in this position then may insert the other screw into the key-hole slot at the opposite end and slide it inwardly to the narrow portion of the slot when the heads of both screws will lie beneath the tool openings K. Then by introducing a tool through the openings K both screws may be adjusted as desired to clamp the binder bars of the device upon the leaves B for permanently holding them in position in the manner illustrated particularly in Figs. 2, 3, 4 and 5.

Having thus described my invention what I claim and desire to secure by Letters Patent is:

1. In a binder, the combination of a pair of binder bars of tubular formation one of which is provided in one wall with a plurality of keyhole slots and the other of which is provided with perforations, a pair of headed screws adapted to be inserted in the keyhole slots, the heads of said screws being accessible through openings in the other wall of said binder bar, and co-operating nuts for the threaded extremities of the said screws, said nuts being inserted in the interior of the other of said binder bars opposite said perforations.

2. In a binder, the combination of a pair of cooperating binder bars of hollow metal construction, a cover-back hingedly connected with each of said binder bars by means of extensions of flexible material covering said binder bars, there being keyhole slots in one of said binder bars and perforations in the other bar, a pair of headed screws adapted to lock leaves in position between said cover backs, the heads of said screws being adapted to co-operate with said keyhole slots, there being threaded extremities on said screws, and threaded means carried in the interior of the other of said binder bars opposite the said perforations and being adapted to receive the threaded extremities of said screws.

3. In a binder, the combination of a pair of co-operating binder bars of hollow metal construction being substantially rectangular in cross-section, there being keyhole slots in one wall of one of said binder bars, a cover-back hingedly connected with each of said binder bars by means of an extension of a piece of canvas wrapped around and adhesively secured to said binder bar, a pair of headed leaf-impaling screws, the heads of said screws being adapted to co-operate with said keyhole slots whereby the said screw heads may rest wholly within the interior of one of said binder bars, there being threaded shanks on said screws, and co-operating threaded nuts accessible through openings in the walls of the binder-bar opposite the said bar provided with keyhole slots.

4. In a binder, the combination of a pair of binder bars of hollow metal construction being substantially rectangular in cross-section, a cover back hingedly connected with each of said binder bars by means of an extension of flexible material which is wrapped around and secured to the exterior of said binder bar, a pair of headed leaf-impaling screws, there being a pair of keyhole slots in one of said binder bars, the expanded openings of which are adapted to take the heads formed upon said leaf-impaling screws, which latter are adapted to pass into the interior of the binder bar opposite the one provided with the said keyhole slots, and threaded nuts adapted for insertion in the interior of the last said binder bar for cooperating with the shanks of said threaded screws whereby the said cover backs with their supporting binder bars may, by the manipulation of said threaded screws, be positively held throughout a range of adjusted positions determined by the length of the threaded portions of said screws.
5. In a binder, the combination of a pair of cooperating binder bars of hollow metal construction, substantially rectangular in cross-section, a cover back hingedly connected with each of said metallic binder bars by means of flexible material which is wrapped completely around and adhesively secured to the respective binder bars, there being keyhole slots on one side of one of the binder bars and a registering opening opposite the contracted portion of each of the keyhole slots on the side of the binder bar opposite the keyhole slots, a pair of screws for adjustably securing the said binder bars together and for locking leaves therebetween, said screws comprising elongated shanks provided with enlarged cylindrical heads at one end thereof adapted to cooperate with the enlarged portions of the said keyhole slots and being of a larger diameter than the contracted portions of the said keyhole slots, the said threaded portions of the screws being adapted to pass through the contracted portions of said keyhole slots, there being registering openings through opposite walls of the other binder bar, and threaded nuts of a size adapted to enter the hollow interior of the last said binder bar whereby they may be engaged by the threaded shanks of the said screws for adjustably positioning the said binder bars in relation to each other by rotation of the said screws, the heads of said screws being accessible through the said cooperating openings in the binder bar provided with the keyhole slots.

In testimony whereof I have signed my name to this specification, on this 12th day of November A. D. 1929.

LLOYD E. GOODYEAR.
